UNITED STATES PATENT OFFICE.

PIERRE E. GUERIN, OF NEW YORK, N. Y.

DESIGN FOR A STANDARD FOR LAMPS, &c.

SPECIFICATION forming part of Design No. 16,857, dated August 17, 1886.

Application filed May 8, 1886. Serial No. 201,608. Term of patent 3½ years.

To all whom it may concern:

Be it known that I, PIERRE E. GUERIN, of the city, county, and State of New York, have invented a new and original Design for Standards for Lamps, &c., of which the following is a full, clear, and exact description, reference being had to the accompanying photograph, making part of this specification, in which a perspective view of my newly-designed standard is shown.

The leading feature of my design consists in the fluted column, the spiral lower part of the same, the base, and the ornamental rods extending from the base up to the lower end of the fluted column.

A represents a fluted column; B, a capital on the same; C, a spirally-grooved lower part below the column; D, a collar at the place where the spirally-grooved part C and the fluted column A unite.

D' is the base of the spirally-grooved part; E, four ornamental legs below the base D'; F, ornamental rods extending from the upper part of the legs E to the collar D, and F' is an ornamented pendant below the base D'.

Having thus described my design, I claim as new and desire to secure by Letters Patent—

1. The design for an ornamental standard for lamps, &c., herein shown and described, the same consisting of a fluted column, A, the collar D, the spirally-grooved part C below the collar, a base, and the ornamental rods F, extending from the base up to the collar D.

2. The design for an ornamental standard for lamps, &c., herein shown and described, the same consisting of the fluted column A, the collar D, the spirally-grooved part C below the collar D, the legs E, and the ornamental rods extending from the collar D to the legs E.

In testimony that I claim the foregoing as my invention I have signed it this 7th day of May, 1886.

PIERRE E. GUERIN.
